TOY CAP DETONATOR

John W. Ryan, 688 Nimes Road, Bel Air, Calif.

Filed Jan. 23, 1964, Ser. No. 78,325

Term of patent 14 years

(Cl. D34—15)

FIG. 1 is a perspective view of the toy cap detonator showing my new design.

FIG. 2 is a side elevational view.

FIG. 3 is a front elevational view.

FIG. 4 is a rear elevational view.

I claim:

The new and ornamental design for toy cap detonator, as shown.
